United States Patent Office

Des. 181,514
Patented Nov. 26, 1957

181,514

DISPLAY BOX FOR WATCHES AND THE LIKE

Francis E. Blod, New Canaan, Conn.

Application October 8, 1956, Serial No. 43,269

Term of patent 14 years

(Cl. D80—5)

Fig. 1.

Fig. 2.

Fig. 3.

Fig. 4.

Fig. 1 is a prospective view of a display box for watches and the like showing my new design;

Fig. 2 is a plan view thereof;

Fig. 3 is a side elevational view thereof; and

Fig. 4 is a rear elevational view thereof.

I claim:

The ornamental design for a display box for watches and the like, as shown.
